UNITED STATES PATENT OFFICE

HYMEN A. BLANCHARD, OF BUFFALO, NEW YORK

LAUNDRY TRAY

Application filed August 7, 1926. Serial No. 127,910.

This invention relates to improvements in laundry trays and more particularly to the drainage fittings for such trays. The invention is applicable to a combination of three trays and its objects are to simplify and reduce the piping by which the trays are connected to the drain line, to minimize the plumbing work and to insure accurate fitting, and to utilize the drainage fitting in reinforcing the bottoms of the trays.

The invention is illustrated in the accompanying drawing in which:

Figure 1 is a sectional view of a three tray combination.

Figure 2 is an elevation of the improved drainage fitting.

As shown in Figure 1 the three cement trays A, B and C are cast as a unit, the intermediate tray B being separated from the tray A by a partition D and from the tray C by a partition E. The improved drainage fitting indicated generally at 1 has a drainage mouth for each of the trays A, B and C and a common discharge nipple to which the drain pipe is connected. The said fitting includes a hollow body 2 having at one side a drainage mouth 3 which communicates with the tray C and at the opposite side a drainage mouth 4 which communicates with the tray B. The body 2 is suitably curved whereby the water entering the mouths 3 and 4 goes downward toward the center of said body and is formed on its bottom or underside with the discharge nipple 5, the arms 6 of the body 2 which connect the said mouths with the discharge nipple 5 preferably being formed along a common curve. The drainage fitting also includes an elongated tubular branch or extension 6 which communicates with one of the arms of the body 2, in this instance the arm which is provided with the mouth 4 and which terminates in a discharge mouth 7 for communicating with the tray A. The extension 6 is preferably tapered toward its discharge end, is inclined downward from the mouth 7 to the point at which it joins the body 2 whereby to facilitate the drainage flow of the water in the tub A and to deliver such water to the body 2 at a point and in a direction which will avoid any liability of

the water backing up into either of the trays B and C, the extension 6 communicating with the body 2 at a point near its bottom and near the nipple 5. The tapering of the extension accelerates the flow of water therethrough and facilitates the continuous removal of suspended matter. The drainage fitting is cast in the bottom of the triple assembly of laundry trays with the body 2 arranged symmetrically under the partition E and with the extension 6 extending transversely through the bottom of the tray B. The drainage fitting is completely embedded in the bottom of the tray combination except for the nipple 5 which provides a common discharge for the three trays and which projects to a suitable extent beyond the bottom of the unit.

The partitions D and E are provided with overflow openings F near the top of the unit and with discharge ducts G extending downward from such openings and the drainage fitting is provided in its upper side with discharge openings 8 and 9 which communicate with the ducts G, the discharge opening 8 being located at the center of the upper side of the body 2 and the discharge opening 9 being located near the outer end of the extension 6.

The drain pipe H requires but a single connection to provide for the complete drainage of the three trays or any one of them, this connection being made in the usual manner with the discharge nipple 5 and being devoid of any complications by which its security is impaired or which require extended plumber's work. All parts of the fitting being enclosed except the discharge nipple 5 it follows that no special form or arrangement of supporting legs for the three trays is required as is frequently the case where the drainage pipes are extended below most of the bottom of the unit.

The extension 6 has the further advantage of bracing or reenforcing the bottom of the unit under the central tray B. In transportation or careless handling during installation three tray units are frequently broken and breakage usually occurs in the bottom of the central tray. By the arrangement shown wherein the extension 6 provides a

reenforcement such liability of breakage is reduced to a minimum.

Having fully described my invention, I claim:

1. In combination a three tray laundry unit of cement and a drainage fitting cast in the bottom of said unit, said fitting comprising a hollow body having two drainage mouths, one communicating with the intermediate tray and the other with an end tray, and an elongated tubular branch having a drainage mouth communicating with the other end tray, said body having a discharge nipple projecting from its under side and said branch being inclined downward toward the point where it joins said body and communicating with the same near its bottom and near said nipple, the drainage fitting being completely embedded in the bottom of said unit except for said nipple which projects below said bottom and is available for connection to a drain pipe.

2. A drainage fitting for a three tray laundry unit comprising a hollow body having two drainage mouths, one to communicate with the intermediate tray and the other with an end tray, said body having at its underside a centrally located projecting discharge nipple, and an elongated tubular extension extending through a portion of the bottom of said unit to reinforce the same, and terminating in a drainage mouth to communicate with the other end tray, said extension being inclined downward toward the point where it joins said body and communicating with the same near its bottom and near said nipple.

3. In combination, a three tray laundry unit of cement and a drainage fitting cast in the bottom of said unit, said fitting comprising a hollow body having two drainage mouths, one communicating with the intermediate tray and the other with an end tray, and an elongated tubular branch having a drainage mouth communicating with the other end tray, said body having a discharge nipple projecting from its under side and said branch being inclined downward toward the point where it joins said body and communicating with the same near its bottom and near said nipple, and wall drains in the dividing walls of said unit and communicating with said hollow body and said branch, respectively, of the fitting, the drainage fitting being completely embedded in the bottom of said unit except for said nipple which projects below said bottom and is available for connection to a drain pipe.

4. In combination a three-tray laundry unit of cement and a drainage fitting cast in the bottom of said unit, said fitting comprising a curved hollow body having at its upper side two drainage mouths, one communicating with the intermediate tray and the other communicating with an end tray

and having at its lower side and substantially centrally thereof a projecting discharge nipple for connection to a drain pipe, said body being also formed with an elongated tubular branch member having a drainage mouth communicating with the other end tray and said branch member being inclined downward to the point where it joins said body and communicating with the same near its bottom and near said nipple, the drainage fitting being completely embedded in the bottom of said unit except for said nipple which projects below said bottom.

5. A drainage fitting for a three-tray laundry unit comprising a curved hollow body having two drainage mouths at its upper side, one to communicate with the intermediate tray and the other with an end tray, said body having at its under side a substantially centrally located projecting discharge nipple, and an elongated tubular extension adapted to extend through a portion of the body of the laundry unit to re-enforce the same and terminating in a drainage mouth to communicate with the other end tray, said extension being inclined downward toward the point where it joins said body and communicating with the same near its bottom and near said nipple, said extension tapering toward its discharge end.

6. In combination a three-tray laundry unit of cement and a drainage fitting cast in the bottom of said unit, said fitting comprising a curved hollow body having two drainage mouths at its upper side, one communicating with the intermediate tray and the other with an end tray, and an elongated tubular branch having a drainage mouth communicating with the other end tray, said body having a discharge nipple projecting at a substantially central point from its underside and said branch being inclined downward toward the point where it joins said body and communicating with the same near its bottom and near said nipple, said branch tapering toward its discharge end, the drainage fitting being completely embedded in the bottom of said unit except for said nipple which projects below said bottom and is available for connection to a drain pipe.

7. A drainage fitting for a three-tray laundry unit comprising a curved hollow body having two drainage mouths at its upper side, one to communicate with the intermediate tray and the other with an end tray, said body having at its underside a substantially centrally located projecting discharge nipple, an elongated tubular extension terminating in a drainage mouth to communicate with the other end tray, said extension being inclined downward toward the point where it joins said body, being of tapering outline from its inlet and to its discharge end, and communicating with said

body near the bottom thereof and near said nipple.

8. A drainage fitting for a three-tray laundry unit comprising a curved hollow body having two drainage mouths at its upper side, one to communicate with the intermediate tray and the other with an end tray, said body having at its underside a substantially centrally located projecting discharge nipple, and an elongated tubular extension terminating in a drainage mouth to communicate with the other end tray, said extension being inclined downward toward the point where it joins said body and communicating with the same near its bottom and near said nipple.

In testimony whereof I affix my signature.
